DESIGN FOR A JUG

Emanuel M. Rosenthal, Detroit, Mich.

Application January 9, 1948, Serial No. 143,615

Term of patent 7 years

(Cl. D44—21)

To all whom it may concern:

Be it known that I, Emanuel M. Rosenthal, a citizen of the United States of America, residing at Detroit, in the county of Wayne and State of Michigan, have invented a certain new, original, and ornamental Design for a Jug, of which the following is a specification, reference being had therein to the accompanying drawing, forming a part thereof, wherein:

Figure 1 is a side elevation of the jug showing my new design; and

Figure 2 is a top plan view of the jug shown in Figure 1.

I claim:

The ornamental design for a jug, substantially as shown.

EMANUEL M. ROSENTHAL.
